Primary Examiner — Sanjeev Paul(74) *Attorney, Agent, or Firm* — Eric Karich; Karich & Associates(57) **CLAIM**

The ornamental design for an infant changing pod, as shown and described.

DESCRIPTION

FIG. 1 is a perspective view of an infant changing pod, showing my new design;

FIG. 2 is a perspective view thereof showing the infant changing pod in an open position;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent unclaimed portions of the infant changing pod and form no part of the claimed design.

1 Claim, 5 Drawing Sheets(56)
